FLOORING

Harold B. Chamberlain, New York, N. Y., assignor to Tuco Products Corporation, New York, N. Y., a Corporation of New York

Application March 5, 1932. Serial No. 597,065

8 Claims. (Cl. 72—70)

My invention relates to new and useful improvements in floorings, and more particularly to a flooring in which there are a plurality of expansion joint strips that are, in turn, securely held to a sub flooring.

One of the objects of the invention is to provide a flooring that is especially adaptable for railway and subway cars.

As is well known, many railway cars and sub-way cars are provided with a concrete or other hard composition flooring to thus withstand the tread of feet, but due to the weaving of the car and the stresses and strains and jolts to which the car is subjected, the flooring is apt to break or crack.

One of the present objects, therefore, is to provide a floor formed of concrete or other hard composition. In fact, the present floors are formed of a composition known in the trade as "Tucolith", although any other similar cementitious floor might be used.

Still another object of the invention is to provide a floor which is especially adapted for cars wherein sub-flooring is used, made up of a number of steel truss plates, across which are placed expansion joint floor strips, so that the car floor surface is, in reality, divided into ten or twelve blocks. Thus, if a rupture happens to occur in the flooring, it will not extend beyond the first expansion strip that it meets. Again, the strips divide the floor into a number of blocks to relieve the composition floor of the strain, due to the weaving of the car.

Still another object of the invention is to provide a steel sub-flooring made up of a plurality of sheets in which there are located supporting clips and on which, in turn, are secured cross strips. Then, covering the sub-flooring and embedding the cross strips is the composition flooring, the cross strips, in reality, dividing the flooring into a number of blocks to thus relieve the floor from the strains due to the weaving of the car or the strains due to expansion and contraction of the composition flooring.

With these and other objects in view, the invention consists in certain new and novel arrangements and combination of parts, as will be hereinafter more fully described and pointed out in the claims.

Referring now to the drawing,

Fig. 1 is a fragmentary sectional perspective of a floor for a car, one of the cross strips being shown embedded in the composition flooring while another cross strip is shown about to be embedded within the composition flooring;

Fig. 2 is a longitudinal view of one of the cross strips, one part of the strip being shown before coating and also showing how the strip rests on the supporting clip, the other half of the strip

being shown with the rubber composition thereon, and the marginal edge being scraped;

Fig. 3 is a top plan view of a portion of the cross strip before the same is coated;

Fig. 4 is a sectional view taken on the line 4—4 of Fig. 3;

Fig. 5 is a similar sectional view but showing the coating as applied to the cross strip.

Referring now more particularly to the several views, and for the moment to Fig. 1, there is shown a sub-flooring 1 made up of a plurality of hollow steel truss plates 2, which provide channels 3 at their adjoining edges where they are riveted, as at 4. These two plates are provided with a plurality of depressions 3', which abut when the plates are placed in their inverted positions and may be riveted together, as at 4', the abutments thus forming a plurality of supporting points between the two plates.

Where the plates are riveted together, there are placed rows of U-shaped clamps 5 and as the plates are practically two and one-half feet between centers, that will space the rows of clamps about five foot intervals throughout the length of the floor.

The number of these U-shaped clamps set along the joints will depend, of course, upon the width of the flooring and as many may be used as desired to support the cross strips now about to be explained.

Referring for the moment to Figs. 2 to 5 inclusive, there is shown preferably a brass strip 6 that is provided with the alternate fins 7 and 8 throughout its length, which fins are simply pressed out on opposite sides of the strip, as may be readily understood.

As before mentioned, the number of strips will depend upon the length of the car, but in an ordinary car there will be thirteen to fourteen of these transversely extending expansion joint floor strips.

Before assembling these cross strips 6, they are subjected to a coating 9 of an elastic composition, preferably a plastic rubber, which will provide a resiliency to take care of the expansion and contraction of the composition and the stresses due to the movement of the car.

After the strip has been completely covered, the composition 9 is removed from the upper edge 10 of the strip for a depth of about one-eighth of an inch, as may be seen in Figs. 1, 2 and 5, the purpose of which will shortly be explained.

Referring for the moment to the right-hand side of Fig. 1, there is shown a fragmentary portion of the strip 6 and resting on the supporting U-shaped clamp 5, the fin 7 bridging the clip and forming a bearing surface for the said strip 6. After the strip is placed in position, a preliminary application of the composition flooring will be poured into the channel to a plane just above the fin 7 of the strip and will be allowed to set so that

the strip will be tightly embedded in its position on the U-clips. In the same manner, the other strips may be embedded throughout the length of the car.

5 After the composition has hardened sufficiently, it will be seen that the strips, including the fins, are rigidly held in place and the main application of the flooring composition is poured.

It will be remembered that, as stated, the elastic composition is scraped from the upper edges of the strips, and the purpose of this is to preclude the possibility of the composition smearing the "Tucolith" flooring composition during the trowelling process.

15 I have found that even though the coating on the cross strip or expansion joint floor strip is scraped for approximately one-eighth of an inch from its top, the trowelling process squeezes the adjacent coating somewhat, so that this coating is pressed upwardly slightly to make up for a part of the one-eighth inch, where it has been scraped off.

Thus, there is no danger of the elastic composition spoiling the effects of the "Tucolith" flooring which may have a pattern or may be of various colors, as desired.

The flooring is then allowed to set and I have found that by providing this sub-flooring and the expansion joint floor strips formed and coated 30 as shown, the possibility of the floor cracking, due to the weaving of the car, is greatly lessened, and should a crack appear after long service, the same will extend only through the block in which it started.

35 It will be understood that although I have shown a special form of steel sub-floor in the drawing, many of the other well-known sub-floors might be utilized, wherein there are channel or arch formations and, in some instances, the cross strips might be set bodily on the channel formations, thus dispensing with the use of spring brackets.

In all instances, however, and regardless of 45 how the cross strip is mounted or the specific shape of the same, the cross strip is to be coated with an elastic material that extends nearly to the marginal upper edge of the cross strip so that the plastic flooring, when setting, may squeeze the plastic coating upwardly of the cross strip, the elastic coating taking care of any expansion or contraction of the plastic floor.

It will be further understood that although I have stated that the structure is one that is 55 preferably used on car floors, it will be appreciated that a surfacing of this kind may be used in all kinds of floors which are to be made up of a cementitious composition, such as concrete floors, sidewalks, roads, and other surfacing of a similar nature.

Again, it will be understood that these cross strips might be set at every joint of the truss plates or the cross strips may be set further apart, the purpose being simply to divide the floor into 65 a desired number of blocks.

Having thus described my invention, what I claim as new and desire to secure by Letters Patent is:—

70 1. A floor comprising a sub-floor formed of hollow steel truss plates having channel formations between said plates, supporting clips secured to the truss plates in certain of said channels, expansion strips mounted on said clips, said channels containing a plastic composition and said

plastic composition also extending over said floor and the floor substantially divided into blocks by said expansion strips.

2. A floor including a sub-floor formed of hollow steel truss plates secured to each other, channel formations between said plates, metal supporting means secured to said plates in certain of said channels, expansion strips mounted on said supporting means, a cementitious composition filling said channels and embedding said expansion strips, said cementitious composition also covering said sub-floor, the expansion strips allowing for the expansion and contraction of the cementitious composition. 30 85

3. A floor including a sub-floor formed of steel truss plates secured to each other and provided with transversely extending channels between said plates, rows of supporting clips in certain of said channels, expansion strips having portions bent outwardly from the vertical to rest on said clips, and an elastic composition on said strips, a plastic composition filling said channels and covering said sub-floor and properly embedding the cross strips. 90 95

4. A monolithic floor for railway cars including a sub-floor formed of hollow steel truss plates, channel formations between said truss plates, rows of supporting means secured to said plates in certain of the said channels, said cross strips having oppositely extending fins mounted on said supporting means, a monolithic composition filling said channels and covering said sub-floor, and the upper edges of the cross strips in a plane with the surface of the monolithic floor. 100 105

5. A sub-floor including hollow steel truss plates having channel formations between said plates, expansion strip supporting means secured in certain of said channels, metal expansion strips having an elastic composition thereon resting on said supporting means, the upper marginal edges 110 115 of said strips, however, being free of said composition.

6. A flooring for railway cars and the like comprising a steel sub-floor of truss and channel formation, cross strips extending along certain of said channel formations, a cementitious flooring filling said channels to embed said cross strips and covering said sub-floor, and said cross strips having an elastic coating thereon and the 120 125 coating extending within a slight distance of the upper marginal edge of said cross strips.

7. A flooring for railway cars and the like comprising a sub-floor made up of steel plates, said sub-floor having channel-like formations formed 130 135 therein, cross strips set in said channel formations, said cross strips provided with an elastic coating extending to a plane near their upper marginal edges, a plastic flooring on said sub-floor and embedding said strips, and the plastic flooring extending flush with the upper edges of said cross strips.

8. A flooring for railway cars and the like comprising a metal sub-floor, the sub-floor having a plurality of arch-like formations formed therein, metal cross strips located between said arch-like formations and extending upwardly in a plane above said arch-like formations, a plastic flooring covering said sub-floor and embedding said cross strips, said cross strips provided with a coating of elastic material, and the said cross strips having their upper edges lying in a plane substantially flush with the said plastic flooring. 140 145
